UNITED STATES PATENT OFFICE.

ELLIS EDGAR HOWSON, OF SALT LAKE CITY, UTAH.

FILTERING DEVICE.

1,070,473.

Specification of Letters Patent. Patented Aug. 19, 1913.

Application filed July 24, 1912. Serial No. 711,354.

To all whom it may concern:

Be it known that I, ELLIS EDGAR Howson, a citizen of the United States, residing at Salt Lake City, in the county of Salt Lake 5 and State of Utah, have invented a new and useful Filtering Device, of which the following is a specification.

My invention relates to improvements in filtering devices in which the filters are sub- 10 merged; and the objects of my improvements are; first, to provide a device for placing and using filter-leaves in several positions; second, arrangements whereby better control is had of the filter-leaves, there- 15 by reducing the wear of the filtering medium and obtaining a more even distribution of residue on the filter-leaves; third, unloading of the residue on the filter-leaves and discharging said residue from a stationary 20 tank containing the filter-leaves by one operation; fourth, placing of the filter-leaves in position for filtering and closing the door in the stationary tank containing the filter leaves by one operation.

I attain these objects by the device illus- 25 trated in the accompanying drawings in which—

Figure 1 is a vertical section with the door closed and the position the tilttable 30 frame assumes while filtering; Fig. 1^a is a vertical section of a part of the tilttable frame showing position assumed from the horizontal to the vertical; Fig. 2 is a vertical section with the door open and the position tilttable frame assumes when material 35 on the filter leaves is being unloaded; Fig. 3 is a vertical section, front view, of the filter leaf in unloading position; Fig. 4 is a vertical section, front view, of the filter leaf 40 in position for filtering; Fig. 5 is a perspective view of a part of the tilttable frame to which the filter leaf is attached; Fig. 6 is a perspective view of the filter frame and a section of the filtering medium; Fig. 7 is a vertical section of the filter leaf attached to 45 the tilttable frame; Fig. 8 is a side view of the outside of an inclined tank set at an angle of about 60° from the horizontal. Fig. 9 is a vertical section, showing the filter- 50 ing apparatus in position for filtering, between the horizontal and vertical. Fig. 10 shows the connection from the outlets o-o.

Similar letters refer to similar parts throughout the several views.

The tilttable frame consists of the follow- 55 ing: two supports b on each of the two sides joined together and held parallel to each by

a plurality of cross-pieces a, parallel to each other. The two sides are held together and parallel by a plurality of shafts C (Figs. 1 60 and 2), the plurality of the long rods d (Figs. 1, 2 and 5), and a plurality of cross-pieces q (Fig. 5) riveted to crosspiece a (Fig. 5). The tilttable frame is carried by the plurality of the shafts C, bearing in the 65 boxes P (Fig. 4), the boxes P are rigidly attached to the interior side of an inclined tank, set at an angle of about 60° from the horizontal (Fig. 4).

The filter leaf (Fig. 7) consists of the fol- 70 lowing: a rigid frame having a sheet iron partition diagonally through it 9^a (Fig. 7), a short pipe O threaded at one end and extending through each side of the frame (Fig. 7), the heavy iron screen 9^c covering 75 the top and bottom sides, the felt 9^b covering the iron screen and the canvas 9^d covering the felt all securely fastened to the frame.

Each filter leaf is attached rigidly to two 80 crosspieces a, one on each side, (the two crosspieces in the same plane) by placing the back end of the filter-leaf under the crosspiece q (Fig. 5) and over the rod d, and bolting the front ends of the filter leaf 85 through the holes s (Fig. 6) to the lugs t (Fig. 5) on the crosspieces a, with the bolts 7 (Fig. 7). The filter leaves, being attached rigidly to two crosspieces a, which are parallel to each other, the filter leaves are parallel to each other and their movements 90 conform to the movements of the crosspieces a, (Figs. 1, 2 and 1^a).

Means by which the filter leaves attached 95 rigidly to the tilttable frame, as described, are moved and held at any angle desired, from the horizontal to the vertical, are as follows: A supporting rod R' (Figs. 1 and 2) is attached to the bottom crosspiece a, on each side of the tilttable frame. To the sup- 100 porting rods R', and midway between the two sides, is attached loosely, the top end of the arm f (Fig. 2). The bottom end of the arm f is attached loosely to a lug in the center of the door g (Fig. 2). Two rests R 105 (Figs. 1 and 2), one on each side of the arm f, are removably secured by the set screws (s') passing through the holes in the base member (s²) of the rests (R) and into the threaded holes in the door g (Fig. 1). 110 Rests (R) of different lengths may be substituted. The door g is hinged at x (Figs. 1 and 2) to the door frame h (Figs. 1 and 2), which is rigidly attached to the bottom of

the inclined tank H (Fig. 1). To the door *g* is attached the lever *m* (Figs. 1 and 2) and the screwwheel *k* (Figs. 1 and 2). Two rings *n* are attached to the lever *m*, to which 5 counterbalances may be attached if desired. The plurality of the shafts *C*, bearing in the boxes *P* (Figs. 3 and 4), act as the main axes. The plurality of the short rods *c* (Figs. 1 and 2), and the plurality of the 10 long rods *d* (Figs. 1 and 2) act as the auxiliary axes.

The filter leaves each having a diagonal partition *9a* (Fig. 7), forming two compartments in each leaf, and each compartment 15 having a separate discharge *O*, makes it possible to filter through both sides at the same time or either side separately, so that in case of a defective filtering medium, only the defective side is put out of commission. 20 A defective filtering medium is disclosed by the turbidity of the solution as it passes through the glass tube *A* (Fig. 4), and the side of the filter leaf showing turbid solution is cut out of commission by means of the 25 valve *A'* (Fig. 4), which controls the passageway to the interior of the compartment covered by the defective filtering medium.

The communication between the outside of the inclined tank and the interior of each 30 compartment of each filter leaf is through the pipe *O* (Fig. 7), which is connected with a union *B'* (Fig. 4) to a rubber tube *B* (Fig. 4). The rubber tube is of such length that it conforms to the different positions the filter leaf assumes during operation. The other end of the rubber tube is connected to a nipple, said nipple extending through the side of the tank *H* (Fig. 4). To the end of the nipple extending through 35 the tank *H* is connected a valve *A'* (Fig. 4), which regulates the communication passageway between the interior of the filter leaves and the outside receptacle *u* (Fig. 4). The glass tube *A* (Fig. 4) is connected to the 40 valve *A'* and the receptacle *u* (Fig. 4).

The manner of operating the filtering device is as follows: The tiltable frame within a stationary inclined tank is held in the desired position by the rests *R* and the 45 closed door *g*. Then the inclined tank is filled with the material to be treated, from a storage tank, said material entering tank through pipe *w* (Fig. 4). The valves *A' A'* (Fig. 4) are opened and with pressure the 50 filtered solution passes into the interior of the filter-leaves through the filtering medium, and from the interior of the filter leaves the filtrate passes to the receptacle *u*, (Fig. 4), through the communication to the 55 outside. By inspection at valve *G* (Fig. 8) it is known when sufficient residue has accumulated on the exterior sides of the filter leaves, then filtering is stopped and any 60

untreated material in tank is returned through pipe *w* to storage tank for untreated material (said pipe *w*, by a valve arrangement acts as an inlet and an outlet to storage tank for untreated material), then by means of the lever *m*, the door *g* is opened which pulls down on the supporting 65 rod *R'* by means of the arm *f*, which tilts the filter leaves to a vertical position. The slight jar on the rubber bumper *z* (Fig. 8) when the frame is tilted and the sudden change of position of the accumulated particles of residue, insure a quick release of the residue from the filter leaves. The residue falls down the inclined bottom of the tank and out of the door *g*. Then, by means of the levers *m*, the door *g* is closed 70 and the rests *R* coming in contact with the supporting rod *R'* raises the tiltable frame to the desired position, (the rests *R* are of various sizes and interchangeable Figs. 1 and 9) for again resuming operations, and 75 holds it there. The door *g* is tightly secured by means of the screw wheel *k*.

I claim:

1. In a filtering device, the combination, of an inclined tank having a movable closure at one end, a tiltable frame suspended within the tank, filter leaves carried by the frame, and means carried by the movable closure for operating the tiltable frame.

2. In a filtering device, a tiltable frame 95 comprising, parallel supporting side members (*b*), parallel cross members (*a*), a plurality of axial coöperative suspending members (*C*), a plurality of coöperating axially binding members (*d* and *e*), a plurality of 100 rigid binding members (*q* and *p*), a supporting member (*R'*) and members (*t*) to which filter leaves are removably secured.

3. In a filtering device, in combination with a receptacle with a movable closure, a 105 hinged arm member (*f*) and removably secured rest members (*R*) on the inner side, and a rigid leverage member (*m*) on the outer side of the movable closure.

4. In a filter leaf, the combination of a 110 frame, filtering media upon the faces of the frame, means within the frame for dividing the same into a plurality of filtering compartments, and a separate controllable outlet communicating with the interior of 115 each compartment.

5. In a filtering device, the combination, of a tiltable frame, filter leaves carried by the frame, means for suspending the tiltable frame, and adjustable means carried by 120 the movable closure for operating the tiltable frame.

ELLIS EDGAR HOWSON.
